UNITED STATES PATENT OFFICE

MICHAEL E. MILLER, OF WASHINGTON, DISTRICT OF COLUMBIA

VALVE

Application filed January 17, 1930. Serial No. 421,550.

(GRANTED UNDER THE ACT OF MARCH 3, 1883, AS AMENDED APRIL 30, 1928; 370 O. G. 757)

The invention described herein may be manufactured and used by or for the Government for governmental purposes without payment of any royalty thereon.

This invention relates to valves, more particularly to automatic, thermostatically controlled valves adapted to regulate the flow of heating, cooling, or other liquid or fluid in a pipe line, and specifically to a valve adapted to be installed in the steam supply pipe of a radiator to control the flow of steam thereto, and that may be adjusted to automatically control the flow of steam to the radiator and maintain the enclosure in which the radiator is located, at a predetermined temperature.

The object of this invention is to provide a simple, durable and inexpensive automatic valve, adapted to be installed in the steam supply line of a radiator, said valve to be located within the enclosure to be heated by the radiator, and be operated thermostatically to control the flow of steam to the radiator and maintain said enclosure at a desired temperature.

A further object is to provide a valve of such a simple character as will permit of its quick adjustment, in a simple manner, when a permanent change or set, of the valve to raise or lower the temperature is desired.

These and other objects will appear in the following description and be finally pointed out in the appended claims, it being understood that slight changes in form and minor details of construction may be resorted to without departing from the scope of the claims.

While a single embodiment of the invention is shown, numerous other applications of the improved valve will be obvious.

Similar numerals indicate corresponding parts in all the figures of the drawings in which:

Fig. 1 is a perspective view of the improved valve and a portion of a radiator.

Fig. 2 is a vertical longitudinal section of the improved thermostatically controlled valve.

Fig. 3 is a horizontal section on line 3-3 of Fig. 2.

Fig. 4 is a horizontal section on line 4-4 of Fig. 2 and

Fig. 5 is a detail section of a fragment of a modified form of the combined reservoir and hand wheel.

Reference now being had to the drawings by numerals, 1 indicates the valve body having the inlet opening 2 adapted to be connected to the steam supply pipe of a radiator, and an opening 3 adapted to be connected with the supply pipe of a radiator.

A screw threaded opening 4 in the top of the valve body is adapted to receive the lower end of a tubular chamber 6 having air opening 7, and an insulating lining 8, said lining having openings corresponding with those in the chamber, and it is through said openings that the room temperature reaches the contents of the bellows located inside the chamber, the blank side of the chamber with its interior insulation being toward the radiator to prevent operation of the valve due to direct heat from the radiator.

The tubular chamber 6 is threaded at its lower end into the valve body, and is provided with a packing box 9, packing 10, packing pressure spring 11, a packing gland 12, and an insulating disk 13 through which the valve stem is mounted for movement, chamber 6 is provided with a head 14, having notches 15 on its upper surface to be further explained.

The valve stem is divided into upper and lower parts 17 and 18 respectively. The upper piston member 17 is threaded in the head 14, extends into chamber 6 and into the upper end of a bellows 19, said bellows at its lower end, being connected to the upper end of the lower piston member 18, which is in turn slidably mounted in the packing box 9. On the lower end of stem 18, a valve disk 20 surrounded by a disk shield 21 is mounted and adapted to function with valve seat 22 arranged in the valve body between the inlet and outlet openings, to control the flow of steam through the valve.

The bellows 19 is mounted at its top on a flange 23, threaded on the stem 17 near its

lower end, said flange having an extension 24, on which nut 25 is threaded. Sealing washers 26 and 27 being arranged between the upper end of the extension of the flange 5 and the interior of the nut and between the lower face of the nut and the flange respectively with the inturned edge of the bellows therebetween adapted to effectively seal the bellows member at its top.

10 At its lower end the bellows has a sealed connection with the stem member 18, there being a flange 28 threaded on the upper end of said stem member, an extension 29 of said flange on which nut 30 is threaded, and sealing washers 31 and 32 arranged between said extension and the nut, and the nut and the flange respectively with the inturned edge of the tube therebetween.

15 In the manner above described, the interior of the bellows is positively sealed, and provides an expansible joint between the adjacent ends of the valve stem members, the upper stem member 17 being threaded into head 14, permits a rotary movement for 20 setting purposes. The lower stem 18 being slidably mounted in the packing box, any expansion or contraction of the contents of the bellows will cause the valve to move to or from the valve seat, to cut off or admit 25 steam to the radiator.

20 To insure the complete return to normal of the bellows after repeated lengthening due to the expansion of its contents, a tensile spiral spring 33, is arranged within the tube 25 and connects the ends of the stems 17 and 18 entering said bellows, the upper and lower ends of said spring being mounted in perforations 34 and 35 in the valve stem members.

40 Upper valve stem member 17 is provided with fluid circulating passages 36 and 37 extending longitudinally through the stem from end to end, said passage 37 continuing through an extension 38 of a part of the lower end of the stem to provide openings 45 into the passages at different levels.

45 Mounted on the upper end of upper stem member 17 is the combined reservoir and hand wheel 39, said reservoir consists of a shell 40 provided with ribs or projections 41, covered by heat insulating material 42, the latter being cut away over air pockets 43 between the ribs 41. Said reservoir is provided with a stem socket 44 in which the upper end of stem member 17 is seated and held in place by set screw 45. An upward extension 46 projects from the top of the socket into the reservoir through which, and adjacent thereto, are provided fluid circulation 50 passages 47 and 48 respectively, in communication at their upper ends with the interior of the reservoir at different levels, the function of said arrangement of openings 55 will appear later.

60 As will be seen by the drawings, the cir-

70 culation passages 47 and 48 in the reservoir and passages 36 and 37 of stem 17 are spaced the same distance apart and are adapted to register with each other when set screw 45 locks the upper end of stem 17 in socket 44, and establish communicating passages between the reservoir 39 and the bellows 19.

75 It will be noted that passage 47 enters the reservoir at a high level and is a continuation of passage 36 of the stem which opens into the bellows at a high level also. Passages 48 and 37 of the reservoir and stem respectively enter the reservoir and bellows at levels relatively lower than the passages 36 and 47 thus setting up a static head in the 80 passages and inducing circulation of the fluid 52 in the reservoir and bellows, the movement being up through passages 36 and 47 and down through 48 and 37, the fluid 52 being preferably highly sensitive to 85 changes in volume with changes of temperature such as kerosene or the like.

90 The upper surface of head 14 of the tubular chamber 6 is provided with notches 15 adapted to be engaged by the lower end of a snap bolt 53 yieldably mounted in the bore of a projection 54 depending from the shell of the combined reservoir and hand wheel, a pressure spring 55 confined in the bore in 95 rear of the bolt tends to force the bolt into the notches and retain said combined reservoir and hand wheel in its adjusted position. Notches 15 may be marked to indicate the temperature at which the valve will 100 automatically cut off the steam, thus providing means whereby the valve may be set to maintain the room at a predetermined temperature.

105 A filling opening 56 closed by plug 57 is provided at the top of the reservoir.

110 The operation of the valve is as follows: After filling the bellows and reservoir with the desired fluid, the valve is set by hand wheel to maintain the room, for instance, at 70 degrees in which position the valve disk may be set one-sixteenth of an inch from the seat 22, thus permitting passage of steam to the radiator, when the temperature of the room has reached 70 degrees said temperature acting on the contents of the reservoir through its air pockets and shell and the action of the temperature of the room, on the contents of the bellows through the 115 openings in its inclosing chamber, said contents will be caused to expand and close the valve. If it is desired to raise the temperature of the room it is simply necessary to back off the valve disk for instance, to three-sixteenths of an inch from the valve seat, thus requiring a higher temperature and greater expansion of the contents of the reservoir and bellows to accomplish the closing of the valve and cutting off of the steam.

120 The modified form of reservoir and hand 125

wheel shown in Fig. 5 of the drawings provides a shell 58 from which extend heat absorbing fins 59 adapted to a reservoir shell highly sensitive to the temperature of the surrounding atmosphere and one that will readily transfer said temperature to the contents of the shell, and promptly close the valve when the maximum temperature desired has been reached.

10 Having thus described my invention what I claim and desire to secure by Letters Patent is:

1. A device of the class described comprising a valve body having inlet and outlet 15 openings, for the flow of temperature changing fluid, a partition provided with a valve seat separating said openings, a chamber open at one side to atmospheric temperature and closed at its ends, mounted on said body 20 with its axis in line with the axis of the valve seat, a valve adapted to co-operate with said seat to control the flow of fluid, said valve having a divided stem, connected by a bellows, a combined hand wheel and reservoir mounted on the stem, passages connecting the interior of the reservoir and bellows and an expansible fluid sealed in said last named parts and adapted to close the valve at a predetermined temperature substantially as and for the purposes specified.

2. A device of the class described comprising a valve body having inlet and outlet 35 openings, for the flow of temperature changing fluid, a partition provided with a valve seat separating said openings, a chamber open at one side to atmospheric temperature and closed at its ends, mounted on said body with its axis in line with the axis of the valve seat, a valve adapted to co-operate with said seat to control the flow 40 of fluid, said valve having stem members threaded through and slidably mounted in opposite ends of said chamber, a bellows connecting the adjacent ends of said stem members, a combined hand wheel and reservoir mounted on the stem, passages connecting the interior of the reservoir and bellows and an expansible fluid sealed in said last named parts and adapted to close the valve at a predetermined temperature substantially as and for the purposes specified.

3. A device of the class described comprising a valve body having inlet and outlet 55 openings, for the flow of temperature changing fluid, a partition provided with a valve seat separating said openings, a chamber open at one side to atmospheric temperature and closed at its ends, mounted on said body with its axis in line with the axis of the valve seat, a valve adapted to co-operate with said seat to control the flow 60 of fluid, said valve having a lower stem member slidably mounted in the lower end 65 of the chamber and an upper stem member

threaded in the upper end of the chamber, a sealed bellows connecting the adjacent ends of the stem members, a combined reservoir, and hand wheel mounted on the upper end of the upper stem member passages connecting the interior of the reservoir and the bellows and expansible fluid sealed in said last named parts and adapted to close the valve at a predetermined temperature substantially as and for the purposes specified.

4. A device of the class described comprising a valve body having inlet and outlet openings for the flow of temperature changing fluid, a partition provided with a valve seat separating said openings, a chamber insulated from external changes of temperature and having openings at one side for the admission of atmospheric temperature to its interior, mounted on said valve body with its axis in line with the axis of said valve seat, a valve adapted to co-operate with the valve seat to control the flow of fluid, said valve having a dividing stem entering the chamber at opposite ends, a bellows connecting the adjacent ends of the divided stem within the chamber, a combined hand wheel and reservoir mounted on the stem adapted to set the valve to operate at different temperatures, passages connecting the interior of the reservoir and bellows and a highly expansible fluid, sealed in said last named parts substantially as described.

5. A device of the class described comprising a valve body having inlet and outlet openings for the flow of temperature changing fluid, a partition provided with a valve seat separating said openings, a closed chamber insulated from external atmospheric changes of temperature and having a packing box at one end, a threaded opening at its other end, said openings at one side for the admission of atmospheric temperature to its interior mounted on said valve body with its axis in line with the axis of said valve seat, a valve adapted to co-operate with the valve seat to control the flow of fluid, said valve having a divided stem entering the chamber at opposite ends, a bellows connecting the adjacent ends of the divided stem within the chamber, a combined hand wheel and reservoir mounted on the stem adapted to set the valve to operate at different temperatures, passages connecting the interiors of the reservoir and bellows and a highly expansible fluid sealed in said last named parts substantially as described.

6. A device of the class described comprising a valve body having inlet and outlet openings for the flow of temperature changing fluid, a partition provided with a valve seat separating said openings, a closed chamber insulated from external atmospheric changes of temperature and having a packing box at one end, a threaded open-

ing at its other end, said openings at one side for the admission of atmospheric temperature to its interior mounted on said valve body with its axis in line with the axis of said valve seat, a valve adapted to co-operate with the valve seat to control the flow of fluid, said valve having a stem divided into two members entering the chamber at opposite ends, one of said members extending from said valve being slidably mounted for axial and rotary movement in said packing box, the other member being threaded through said threaded end, a bellows connecting the adjacent ends of the divided stem within the chamber, a combined hand wheel and reservoir mounted on the stem adapted to set the valve to operate the different temperatures, passages connecting the interiors of the reservoir and bellows and a highly expansible fluid sealed in said last named parts substantially as described.

7. A device of the class described comprising a valve body having inlet and outlet openings, for the flow of temperature changing fluid, a partition provided with a valve seat separating said openings, a chamber open at one side to atmospheric temperature and closed at its ends, mounted on said body with its axis in line with the axis of the valve seat, a valve adapted to co-operate with said seat to control the flow of fluid, said valve having stem members threaded through and slidably mounted in opposite ends of said chamber, a bellows connecting the adjacent ends of said stem members, a combined hand wheel and reservoir mounted on the stem having a shell, insulated ribs and air pockets adapted to transfer the exterior atmospheric temperature to the interior of the reservoir, and provide means for setting the valve, passages connecting the interiors of the reservoir and bellows and an expansible fluid sealed in said last named parts adapted to close the valve at a predetermined temperature substantially as and for the purposes specified.

8. A device of the class described comprising a valve body having inlet and outlet openings, for the flow of temperature changing fluid, a partition provided with a valve seat separating said openings, a chamber open at one side to atmospheric temperature and closed at its ends, mounted on said body with its axis in line with the axis of the valve seat, a valve adapted to co-operate with said seat to control the flow of fluid, said valve having stem members threaded through and slidably mounted in opposite ends of said chamber, a bellows connecting the adjacent ends of said stem members, a combined hand wheel and reservoir mounted on the stem having a shell, insulated ribs and air pockets adapted to transfer the exterior atmospheric temperature to the interior of the reservoir,

and provide means for setting the valve, passages connecting the interiors of the reservoir and bellows and an expansible fluid sealed in said last named parts and co-operating means arranged on the chamber and combined hand wheel and reservoir to indicate the set of the valve.

9. A device of the class described comprising a valve body having inlet and outlet openings, for the flow of temperature changing fluid, a partition provided with a valve seat separating said openings, a chamber open at one side to atmospheric temperature and closed at its ends, mounted on said body with its axis in line with the axis of the valve seat, a valve adapted to co-operate with said seat to control the flow of fluid, said valve having stem members threaded through and slidably mounted in opposite ends of said chamber, a bellows connecting the adjacent ends of said stem members, a combined hand wheel and reservoir mounted on the stem having a shell, insulated ribs and air pockets adapted to transfer the exterior atmospheric temperature to the interior of the reservoir, and provide means for setting the valve, passages connecting the interiors of the reservoir and bellows and an expansible fluid sealed in said last named parts, graduated notches arranged on the upper face of the chamber and a slip bolt mounted on the combined hand wheel and reservoir adapted to engage said notches and indicate the temperature at which the temperature changing fluid will be cut off.

10. A device of the class described comprising a valve body having inlet and outlet openings, for the flow of temperature changing fluid, a partition provided with a valve seat separating said openings, a chamber open at one side to atmospheric temperature and closed at its ends, mounted on said body with its axis in line with the axis of the valve seat, a valve adapted to co-operate with said seat to control the flow of fluid, said valve having stem members threaded through and slidably mounted in opposite ends of said chamber, a bellows connecting the adjacent ends of said stem members, a combined hand wheel and reservoir mounted on the stem, an expansible fluid sealed in said reservoir and said bellows, and passages in the stem connecting said parts entering same at different levels and adapted to induce circulation between same, substantially as shown.

11. A device of the class described comprising a valve body having inlet and outlet openings, for the flow of temperature changing fluid, a partition provided with a valve seat separating said openings, a chamber open at one side to atmospheric temperature and closed at its ends, mounted on said body with its axis in line with the axis of the valve seat, a bellows within said chamber

ber, a valve adapted to co-operate with said seat to control the flow of fluid, said valve having a divided stem, the adjacent ends of its members entering the bellows, a combined hand wheel and reservoir mounted on one of the stem members, extensions at the ends of said last mentioned stem member projecting into the reservoir and bellows and passages entering through the stem, one 10 passing through the extension of the stem in the reservoir, the other through its extension in the bellows, and entering said parts at different levels, adapted to induce circulation of fluid between said parts due to 15 static head, and an expansible fluid sealed in said reservoir and bellows, adapted to close the valve at a predetermined temperature substantially as described.
